Primary Examiner—James Gandy*Assistant Examiner*—Cathron B. Matta*Attorney, Agent, or Firm*—Stetina Brunda Garred & Brucker[57] **CLAIM**

The ornamental design for a sports indicative closure cap, as shown and described.

DESCRIPTION

FIG. 1 is a front top perspective view of the sport indicative closure cap of the present invention showing my new design; and,

FIG. 2 is a rear bottom perspective view thereof. The broken line showing of the interior of the closure cap forms no part of the claimed design.
